CLAIM

The ornamental design for an underwater robot set as shown and described.

DESCRIPTION

FIG. 1 is a rear, left and top perspective view of an underwater robot showing my new design;

FIG. 2 is another rear, left and top perspective view thereof;

FIG. 3 is a front, right and top perspective view thereof;

FIG. 4 is a front, right and bottom perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines shown in the figures depict portions of the underwater robot that form no part of the claimed design.

1 Claim, 10 Drawing Sheets
